UNITED STATES PATENT OFFICE.

CARSON E. DIXON AND JAMES H. BOONE, OF HENRIETTA, NORTH CAROLINA.

SPLIT PICK-CAM HUB.

Application filed January 11, 1923. Serial No. 612,071.

To all whom it may concern:

Be it known that we, CARSON E. DIXON and JAMES H. BOONE, citizens of the United States, residing at Henrietta, in the county of Rutherford and State of North Carolina, have invented certain new and useful Improvements in a Split Pick-Cam Hub, of which the following is a specification.

Our invention relates to a split cam hub 10 and has for an object to provide a device of this character, that can be placed on and removed from a shaft without disconnecting any of the other elements of the machine on which this invention is used.

15 A further object of our invention is to provide a split pick cam hub, that may be used in conjunction with the cam shaft of any type of machine now in use, that is so constructed that should the set screw 20 break the hub may be removed from the cam shaft without the necessity of injuring the other elements of the same.

A still further object of our invention is to provide a split pick cam hub that is 25 strong, durable, very simple and inexpensive in construction, and that is especially well adapted to the uses for which it is designed.

Other objects and advantages of the 30 invention will become apparent during the course of the following description.

In the drawings, wherein like numerals are employed to designate like parts throughout the same,

35 Figure 1 is a perspective view of our invention,

Figure 2 is a top plan view of the same, and

40 Figure 3 is an end view thereof.

In the drawings, wherein for the purpose of illustration is shown a preferred embodiment of our invention, the numeral 5 designates a cam shaft of a loom.

45 Our invention is restricted to the construction of the cam hub, that is adapted to hold the pick cam which runs the picker stick, and therefore the cam is not illustrated. The cam hub comprises a pair of semicylindrical sleeve sections 6 and 7. The 50 sleeve sections 6 and 7 are provided near one end thereof, with the transversely or angularly extending flanges 8 and 9 respectively, through which are adapted to pass bolts 10 by which means the split pick

cam hub is fastened on the cam shaft 5. 55 Diametrically opposed arms 11 and 12 are formed integral with the sleeve sections 6 and 7 respectively, said arms being disposed at right angles to the longitudinal axis of the shaft 5. The arm 12 is substantially 60 longer than the arm 11, and gradually tapers from its base. One edge of the arm 12 is formed with a concave surface 13, the curved edge 13 being provided so that the adjustable screw in the cam will hold 65 straight to the arm. The arm 11 which is substantially shorter than the arm 12, is also a tapering arm and is provided to aid in the holding of the cam to the hub. The arms 11 and 12 are provided with the transversely extending apertures 14 and 15 respectively, by which means the cam is fastened 70 to the arm. The arm 12 is made longer than the arm 11, so that the cam may be adjusted by means of the adjustable screw 75 carried by the cam. The cam is seated on the ends 16 and 17 of the sleeve sections 6 and 7, as will readily be understood. The sleeve sections 6 and 7 are placed on the shaft 5, and held in place by means of a 80 set screw or a plurality thereof 18.

In use, a pair of sleeve sections similar to the sections 6 and 7 respectively, are placed on the cam shaft 5 of a loom, and held securely together by means of the bolts 85 10 which pass through the flanges 8 and 9 respectively. The set screws 18 are then tightened so as to grip the cam shaft 5, and the split pick cam hub is in place. The cam may then be associated with the hub, 90 being seated upon the ends 16 and 17 of the sleeve sections 6 and 7, and fastened in the desired adjusted position to the arms 11 and 12 respectively. By means of the long arm 12, having the curved edge 13, the cam may be adjusted as desired, and held in any desired position by means of the apertures 15 and 14. This split pick 95 cam hub can be made to hold any pick cam on any loom that is now in use, and therefore it may be said that this improved form of cam hub may be adapted for universal use on looms.

100 It is to be understood that the form of our invention herewith shown and described is to be taken as the preferred embodiment of the same, and that various changes in the shape, size and arrangement of parts

may be resorted to without departing from the spirit of the invention or the scope of the subjoined claim.

Having thus described our invention, we

5 claim:—

A split hub for the cam of a picker stick comprising a pair of like companion semi-cylindrical sleeve sections, radially extending abutting attaching flanges formed on

10 the sleeve sections, removable means extending through the flanges for detachably

connecting the sections together, cam attaching arms formed on the sections at the ends of said flanges, means for securing the sections on a shaft for movement therewith, and extensions formed on the sections extending beyond the flanges and arms.

15 In testimony whereof we affix our signatures.

CARSON E. DIXON.
JAMES H. BOONE.
